UNITED STATES PATENT OFFICE.

EMERY PARKER, OF NEW BRITAIN, CONNECTICUT, ASSIGNOR TO THE
NASHUA LOCK COMPANY, OF NASHUA, NEW HAMPSHIRE.

LOCK.

SPECIFICATION forming part of Letters Patent No. 249,789, dated November 22, 1881.

Application filed June 11, 1881. (Model.)

To all whom it may concern:

Be it known that I, EMERY PARKER, of New Britain, in the county of Hartford and State of Connecticut, have invented certain new and useful Improvements in Locks; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

My improvement relates to door-locks, and particularly to such as are intended to be used in hotels and similar buildings where it is desirable to have locks which cannot be opened from the outside when locked upon the inside of the room.

The object of my invention is to provide a lock which can be locked and unlocked in the usual manner from the outside when it is not locked upon the inside, and which in the latter case cannot be unlocked from the outside, and one which can be locked or unlocked from the inside at all times, whether it is locked or not from the outside.

In the accompanying drawings, illustrating my invention, Figure 1 is a side view of a lock having my improvements, with part of the front plate removed, so as to show the interior parts in the unlocked position. Fig. 2 is a somewhat enlarged view of the lower part of the lock, showing the several parts in the position when locked from the inside and the bit of the key in the lock. Fig. 3 is a vertical section on the line *a b* of Fig. 2.

A is the case of the lock, which is made in the ordinary manner.

B is the key-hole upon the outside of the door, and *C* shows the position of the key-hole upon the inside of the door, they not being opposite to each other. The position of the inside key-hole is shown by dotted lines in Fig. 2.

D is the bolt, *E* the tumblers, and *F* the springs, all operated in the usual manner, and constructed with two sets of notches for the key when used in either of the two key-holes.

The lock may be made in almost any of the

ordinary forms, and, so far as my present invention is concerned, the bolt might be without tumblers.

G is a sliding block lying between and guided by the plates of the lock-case, and also by the stud or projection *H*, which limits the movement to the rear to the position shown in the drawings.

J is a spring which presses the block *G* to the rear, and which can be compressed by the block *G* in moving forward or to the left, as shown in the drawings. The upper right-hand corner of the block *G* is slightly beveled to receive the bit of the key, (shown without the key in Fig. 1, and with the bit of the key resting upon it in Fig. 2.)

K is the bit of the key in the position when inserted upon the inside of [the] door and the bolt locked.

The operation of my invention is as follows: In the position of the parts shown in Fig. 1 the key can be inserted from the outside through the key-hole *B*, and the bolt locked or unlocked in the usual manner. When the key is inserted from the inside to lock the bolt it can be turned round to the position shown in Fig. 2. This throws the bolt and leaves the bit of the key resting upon the block *G*, in which position it acts as a pawl against the bolt to hold it from being forced back if another key should be used from the outside to unlock the door. As the bit of the key cannot pass this position it cannot be removed from the lock, and consequently must remain a sure preventative against the lock being opened from the outside until it is unlocked from the inside.

If by accident the door should be locked from the outside while a person having a key was upon the inside, as might sometimes occur, the bolt can be unlocked from the inside, whether another key remains in the outside or not. In this case the bit of the key in turning the reverse way from the locking presses against the side of the block *G* and forces it forward against the spring *J*, and passes upward to the bolt, which it throws in the usual manner. The key can then be passed around, so as to be taken out of the key-hole, if desired. By means of my invention an ordinary lock can

be made secure and unpickable when locked from the inside without interfering with any of the ordinary advantages of a simple lock.

What I claim as my invention is—

5 In a door-lock, the combination of the sliding block G and spring J, constituting a stop mechanism which permits the bit of the key

to pass in one direction to withdraw the bolt, but stops said key when the bolt is locked, substantially as described.

EMERY PARKER.
